UNITED STATES PATENT OFFICE

96,557

DESIGN FOR A NEON SHRINE CRUCIFIX

Salvatore Lucchesi, Bronx, N. Y.

Application July 6, 1935, Serial No. 57,546

Term of patent 7 years

To all whom it may concern:

Be it known that Salvatore Lucchesi, a citizen of Italy, residing at the Bronx, in the county of the Bronx and State of New York, has invented a new, original, and ornamental Design for a Neon Shrine Crucifix, of which the following is a specification, reference being had to the accompanying drawing, forming part thereof.

In the accompanying drawing:—

Fig. 1 is a front elevational view of a neon shrine crucifix showing my new design.

Fig. 2 is a fragmentary edge elevational view of Fig. 1 looking in the direction of the line 2—2 of Fig. 1.

Fig. 3 is a fragmentary enlarged sectional view taken on the line 3—3 of Fig. 1.

I claim:

The ornamental design for a neon shrine crucifix as shown and described.

In testimony whereof I affix my signature.

SALVATORE LUCCHESI.
